(57) **CLAIM**

The ornamental design for a dead bolt reinforcing plate including vertically offset holes for receiving fasteners therethrough, as shown and described.

DESCRIPTION

FIG. 1 is a front elevational view of a dead bolt reinforcing plate including vertically offset holes for receiving fasteners showing my new design;

FIG. 2 is a rear elevational view thereof;

FIG. 3 is a right side elevational view thereof;

FIG. 4 is a left side elevational thereof;

FIG. 5 is a top plan view thereof; and,

FIG. 6 is a perspective view thereof.
